UNITED STATES PATENT OFFICE.

FRANKLIN MARSH, OF MILWAUKEE, WISCONSIN, ASSIGNOR OF ONE-HALF TO
ALEXANDER C. GRANT, OF MILWAUKEE, WISCONSIN.

WINDOW.

1,145,159.

Specification of Letters Patent. Patented July 6, 1915.

Application filed May 4, 1914. Serial No. 836,350.

To all whom it may concern:

Be it known that I, FRANKLIN MARSH, a citizen of the United States, and resident of Milwaukee, in the county of Milwaukee and State of Wisconsin, have invented certain new and useful Improvements in Windows; and I do hereby declare that the following is a full, clear, and exact description thereof.

My invention has for its object to provide a window capable of resisting climatic conditions, whereby it will not be blurred through the accumulation of moisture or frost thereon, the invention being particularly adapted for use in locomotive cabs, pilot houses, street cars, show windows, or wherever it is desirable to maintain a clear view.

In the arrangement and construction of my device I provide a sash having a single pane of glass therein, to which sash is detachably secured an apertured circulating pipe, the apertures being staggered with relation to each other, whereby jets of heated compressed air are discharged across the surface of the glass to thus evaporate moisture deposited thereon.

The invention also contemplates providing means for securing the circulating pipe and single pane of glass in their relative positions upon the sash-frame, and to provide means whereby the sash is hinged, one of the hinge members being utilized as a coupling connection, whereby the air is delivered to the circulating pipe.

With the above objects in view the invention consists in certain peculiarities of construction and combination of parts as hereinafter set forth with reference to the accompanying drawings and subsequently claimed.

In the drawings Figure 1 represents a sectional end elevation of a locomotive cab having a window therein embodying the features of my invention; Fig. 2, a detailed cross-section of the window, the section being indicated by line 2—2 of Fig. 1; Fig. 3, a fragmentary elevation of my preferred form of window construction with parts broken away and parts in section to illustrate certain structural features, and Fig. 4, an enlarged detailed cross-section of my preferred form of window construction, the section being indicated by line 4—4 of Fig. 3.

Referring by characters to the drawings, 55 1 represents a valve-controlled steam-pipe

for supplying heat to a drum 2, which drum is provided with a vent-cock 2', whereby the drum may be relieved of condensation. The drum encircles a coil of pipe 3, the feed end 3' of which coil of pipe extends through a 60 stuffing-box at one end of the drum and the discharge end 3'' extends through a stuffing-box in the opposite end of said drum, as shown, it being understood that the feed end of this air pipe is connected to a suitable 65 source of air under pressure. The right-hand side of the cab is shown as having a window sash 4 hinged thereto, which sash is provided with a standard pane of glass 5. Secured to the stiles of the sash by clamps 6 70 are pipe sections 7 having discharge apertures 8 that are staggered with relation to each other. The upper and lower ends of these pipe sections are connected by cross-pipes 7', 7'', respectively, the cross-pipe 7' 75 being, in turn, connected to the discharge end 3'' of the air supply pipe or coil 3 by a valve-controlled pipe section 9. By this arrangement it will be observed that as the air passes through the coils within the heated 80 drum, that said air is tempered to the proper degree and thereafter is discharged into the apertured pipe sections 7, 7', from which the air jets are directed upon the face of the pane of glass, the said jets being staggered 85 with relation to each other, whereby the full area of the glass is subjected to the heat influence, to thus prevent the same from clouding up by frost or moisture.

Referring to Figs. 3 and 4 showing the 90 preferred construction, the sash-frame 4' is channeled out to receive the pane of glass 5', the edges of which pane are arranged to seat against a rubber or leather gasket strip 10. The glass is held in its position within 95 the frame and against the gasket by means of pairs of lugs 11 having rubber buttons 11' that abut the adjacent face of the glass. These lugs 11 are apertured for the reception of the threaded shanks 12 of bolts having hooked ends 12', the said shanks being passed through apertures with which the sash-frame members are provided. The hook-ends of these bolts serve as clamping members for vertically disposed apertured discharge pipe sections 13, one of which sections only is shown. These sections are connected at the top and bottom of the sash-frame by cross-pipes 13', 13''. The upper cross-pipe 13' is provided with a down- 100 105 110

turned tapered nozzle-end 14, which end is fitted into a hollow hinge bracket 15. This bracket 15 has tapped therein an air feed-pipe 9', whereby air is delivered to the circulating pipes about the window-pane, the said nozzle 14 constituting a hinge-pintle. The cross-pipes 13', 13'', in this instance are also apertured, whereby the transverse jets of air from the pipes 13 are intersected by longitudinal jets discharged from the apertures in the cross-pipes. The lower cross-pipe 13'' and one longitudinal pipe stretch are connected at one corner by a coupling member 16, which member has extending therefrom a pintle 17 that is in axial alinement with the discharge nozzle 14 and is adapted to be seated in a hinge lug 17', the said hinge lug and bracket 15 being secured to the wall of the cab member. By this construction the window may be swung open without disconnecting the air supply and furthermore should a pane of glass be broken a substitute can readily be inserted by simply disconnecting the clamping lugs 11 from the shanks of the bolts 12, which shanks are provided with threaded ends for the reception of nuts 12'', whereby the lugs and pipe

members are all securely gripped to the sash, it being understood that when the nuts 12'' are removed the apertured pipes 13 are also disconnected from the sash, this construction being both effective and economical from a manufacturer's standpoint. 30

I claim:

In a window for the purpose described 35 having a casing, a glass fitted to one face of the casing, and a fluid pipe fitted about the opposite face of said casing; the combination of a combined attaching means for the pipe and glass comprising apertured 40 lugs for engagement with the edges of the glass, bolts fitted through the lug apertures and casing having hooked ends for engagement with the pipe, and clamping nuts for the bolts engageable with the lugs. 45

In testimony that I claim the foregoing I have hereunto set my hand at Milwaukee in the county of Milwaukee and State of Wisconsin in the presence of two witnesses.

FRANKLIN MARSH.
